TETHER BALL PROJECTOR AND CATCHER TOY

Jack R. Bedient, 55 Richardson Drive,
Henderson, Nev. 89015

Filed June 8, 1971, Ser. No. 151,165

Term of patent 14 years

Int. Cl. D21—01

U.S. Cl. D34—15

FIG. 1

FIG. 2

FIG. 1 is an elevational view of a tether ball projector and catcher toy showing my new design, and being identical from all sides, and

FIG. 2 is a top plan view thereof.

I claim:

The ornamental design for the tether ball projector and catcher toy, as shown and described.
